INVENTOR:

EUGÈNE VAN DE VOORDE.

ATTORNEY.

UNITED STATES PATENT OFFICE.

EUGÈNE VAN DE VOORDE, OF BREMEN, GERMANY.

SMOKER'S PIPE.

Application filed August 31, 1921. Serial No. 497,294.

To all whom it may concern:

Be it known that I, EUGÈNE VAN DE VOORDE, a citizen of Germany, and resident of Bremen, Germany, have invented certain 5 new and useful Improvements Relating to Smokers' Pipes, of which the following is a specification.

The pipes used until to-day present several drawbacks, viz the smoke enters the mouth 10 at a too high temperature; the tobacco becomes wet in the bowl after it is lighted, whereby the combustion is irregular and the taste of the smoke unpleasant, and, owing to the moisture which accumulates at the bottom 15 of the bowl, the lower layer of tobacco becomes wet and does not burn; furthermore the heavy nicotines are carried with the smoke through the stem and mouthpiece of the pipe and enter the mouth of the 20 smoker and finally said pipes are difficult to keep clean.

When smoking a cigar, the above drawbacks are not experienced, and whilst studying the various stages of combustion of a 25 cigar and inhaling the resulting smoke, I made it my study to arrange a pipe in which the conditions of combustion of the tobacco and inhaling of smoke are similar to the corresponding conditions when smoking a 30 cigar.

Owing to the irregular layers of tobacco leaves from which a cigar is made, the smoke reaches the mouth after flowing slowly through many windings and the pores of 35 the tobacco leaves effect the function of compensators of the temperature whereby they give back to the outer air, the moisture of the air inhaled through the cigar by the smoker and the moisture contained in the 40 tobacco, whilst the cigar is kept dry.

In the novel pipe, which is the object of the present invention, the above conditions of combustion are got by making use of a bowl made of highly porous burnt clay 45 which readily absorbs the moisture; however after a short time such bowls become saturated with moisture and heavy nicotines, proceeding from the tobacco and obstructing the pores of the clay and should 50 be replaced by a fresh one. For this reason the bowls are made interchangeable, and in order to manufacture same at a low cost, and in large quantities, they should be of simple shape.

55 In order to cool the smoke in the same way as in a cigar, the pipe proper or tube is

made of a heat conducting material, and preferably of aluminium. The walls should be thin and the diameter large and the cross section should be uniform from the bowl to 60 the mouthpiece, in order that the smoke may flow slowly through same. In the interior of the tube is inserted a bundle of fine aluminium chips or wire having for its object to uniformly distribute the smoke within the 65 tube. This bundle of chips or wire, which I call a "diffuser," is in direct contact and metallic connection with the wall of the metal tube. In such conditions the smoke from the bowl slowly and uniformly flows 70 through the whole section of the tube where it is cooled by the diffuser, and the heat absorbed by the latter passes by conductivity to the wall of the tube and then to the outer air. Owing to this efficient cooling of 75 the smoke, a condensing of the heavier nicotines occurs. These substances of a biting and burning taste, are violent poisons, but the carriers of the flavour and taste of the burnt tobacco, are not eliminated from the 80 smoke, so that the charm and enjoyment of the smoker are highly increased.

It seems that the cooling power of the pipe proper upon the smoke should be increased by providing same with ribs or corrugations. 85 However I have found that when polishing the outer face of the metal tube, the cooling is more efficient owing to the radiation of heat.

The mouth piece is made of ebonite or like 90 bad heat conductor; its temperature is higher than that of the pipe proper, so that no further condensing of non-volatile substances occur in the mouthpiece and no more nicotines enter the smoker's mouth. 95

The most convenient shape of a pipe is that of a hook or an U, as such pipes hang naturally from the smoker's mouth and are held by the teeth. Furthermore the axis of the bowl is continuously maintained in a 100 vertical direction, which facilitates a uniform combustion and prevents the dropping of the ashes.

A tight joint between the mouthpiece and pipe is secured by means of a ring made 105 from a resilient material such as soft rubber, in order to reduce the shocks resulting from the motions of the smoker, so that the teeth of the latter are not exposed to strains. Such joint is efficient, easy to take to pieces, 110 and to clean.

In order to clean the pipe, the bowl and

mouthpiece are removed and the pipe proper, with the diffuser, are plunged in boiling water, whereby it is thoroughly cleaned and any smell is removed.

5 The novel pipe, provided with the above mentioned improvements is shown by way of example in the accompanying drawing, in which:

10 Figs. 1 and 2 show axial sections of two constructive forms of same.

Fig. 1 shows a pipe in which the pipe proper 2, made of aluminium, is hook shaped, whilst the pipe of Fig. 2 is formed of a cylindrical portion 2^a and an elbow portion 2^b conveniently connected together.

15 In both constructive forms said pipe has a uniform section of large diameter.

3 designates the diffuser formed by means of fine chips or wire of aluminium through 20 which the flowing smoke is cooled and purified from its nonvolatile substances. The outer face of pipe 2 or 2^a 2^b is polished in order to readily transmit the heat to the outer air by radiation as well as by convection and contact.

30 Bowl 1 is made of very porous brunt clay and slightly conical on its outer and inner face, in order to make the manufacture of same more easy. The bottom part 6 is thick as it is more exposed to the moisture than the lateral walls which are thin, in order to allow the steam, produced during the combustion of the tobacco, from readily escaping through the pores of the walls, 35 whereby the tobacco is kept dry and may be wholly burnt.

35 The mouthpiece 4 made of gutta percha or the like material, is provided with a thicker end portion 7 inserted into the pipe 40 2 and provided with an annular groove 8

45 into which is inserted a ring 5 of smooth rubber or the like resilient material and having a circular or square section, said ring forming a tight joint between both parts 2 and 4.

50 At the end of the pipe 2 (2^a) are provided two small semi-circular grooves 9 in which are inserted spring rings between which the ring 5 may slightly move in order to secure a resilient joint.

55 The various parts of the pipe are so arranged and combined as to comply with the conditions of combustion of tobacco and for cooling the smoke and freeing it from nicotine.

The pipe is furthermore simple, light and may be readily cleaned.

60 Having now fully described my said invention, what I claim and desire to secure by Letters Patent, is:

65 A smoker's pipe, comprising a bowl, a mouth piece formed near one end with a groove, a tubular portion extending between the bowl and the mouth piece, said tube-like portion being of heat conductive material and substantially of uniform diameter, a resilient washer fitted in the groove in the mouth piece and engaging the inner surface of the tubular portion, said tubular portion being formed with a groove above and below the resilient washer, springs 70 mounted in the last mentioned grooves to hold the resilient washer against displacement, and a metallic heat diffuser in the tube-like portion to conduct the heat of the smoke to the tube-like portion for radiation.

75 In testimony whereof I have hereunto set my hand.

EUGÈNE VAN DE VOORDE.
